BLADE GRINDING MACHINE

Hermann Hill, Bridgeport, Conn., assignor to
 Magazine Repeating Razor Company, New
 York, N. Y., a corporation of New Jersey

Application June 3, 1941, Serial No. 396,381

15 Claims.

(Cl. 51—78)

The object of the invention is a machine for grinding a cutting edge on a margin of a continuously traveling strip of blade making material.

More specifically, the object is to provide for secure and definite alignment of the strip as it travels with respect to the grinding tools for altering the grinding angle at will.

Further objects will appear in the course of the explanation of the invention.

Briefly describing the drawings.

Fig. 1 is a diagrammatic plan view showing a machine in which the invention may be incorporated;

Fig. 2 is a plan view of a grinding unit;

Fig. 3 is a view on the line 3—3 of Fig. 2;

Fig. 4 is a view on the line 4—4 of Fig. 3;

Fig. 5 is a view on the line 5—5 of Fig. 4;

Fig. 6 is a plan view of part of a grinding unit with parts broken away to show details;

Figs. 7, 7a, 7b, and 7c are series of views showing the changing section of a blade strip as it passes through successive guide rolls and also showing the contours of the rolls;

Fig. 8 is an enlarged view partly in section of a blade guide;

Fig. 9 is an isometric view of a thrust block.

Fig. 10 is a fragmentary view showing the variation in the angle of the face of the thrust block for causing a change in the grinding angle.

In describing the machine and its component units, the side of the machine that is uppermost on the sheet in Fig. 1 will at times be referred to as the "right" or "right-hand" side of the machine and that side which is lowest on the sheet will at times be referred to as the "left" or "left-hand" side of the machine.

The units that make up the machine are two grinding units A and A', three honing units B, B', and B'', five wiping units C, C', C'', C''' and C''', a strip feeding unit D, a breaking unit E, and a stacking unit F. The number of grinding units and the number of honing units may, of course, be increased or under some circumstances reduced, but it has been found that the number of each as given is sufficient to bring a strip to a sharp cutting edge, and therefore it is adopted for commercial work.

The stock or blade strip M which is to be ground and honed as it passes through the machine is drawn from a conventional reel (not shown) located in advance of the first grinding unit. In dimensions it would vary in width from say .300" to perhaps 1" and in thickness perhaps from .003" to .012", and its margins are provided with pairs of opposite notches 9, 9, each successive pair being spaced a blade length from the preceding pair. The purpose in providing the notches is for co-operation with the breaking

unit, which however has nothing to do with the invention claimed in this application.

As both grinding units are identical except for differences arising out of changes in the strip guiding means as the strip passes successive grinding wheels, only the first grinding wheel mechanism of unit A will be described in full, the differences between succeeding wheels and associated mechanisms being pointed out hereafter.

10 The working parts are supported on a table 10 mounted on a conventional frame 11. The grinding tools comprising the rotatably mounted wheels 12 and 13 of bonded abrasive material are mounted respectively on hangers 14 and 15 by means of stub shafts 16 and 17. The hangers are suspended from non-rotatably mounted shafts 18 and 19 upon which they may swing independently of each other transversely of the longitudinal centerline of the machine. They may, if desired, be located in selected angular position by means of the split clamp collars 18a and 19a, but preferably these collars are drawn up only tight enough so that they clamp the shafts without play but are nevertheless rotatable without disturbing them. They are prevented from sliding along the shafts by split collars 18b and 19b surrounding the shafts. The grinding wheels are therefore capable of movement independently of each other toward and away from the blade strip M. To adjust them accurately to grinding position and to maintain them in position after adjustment, I provide the links 20 and 21 with actuating mechanism. The link 21 is pivotally connected to the hanger 15 as shown at 22 and to 20 the block 23 as indicated at 24. The block 23 is slidably mounted in the track member 25 and is retained in sliding contact by the gibbs 29a and 21a and has a threaded bore to receive the non-traversing screw 26 at the end of the shank 21. The shank 27 passes through the bearing 28 and is fixedly secured to a bracket 22a against longitudinal movement by the collars 29 and 30 fixedly mounted on it. Assuming that the screw 26 has a right-hand thread, rotation to the right of the hand wheel 31 fixedly mounted on the shank 27 draws the grinding wheel 13 (when the collar 19a is loosened) toward the blade strip, and rotation to the left moves it away from the blade strip.

50 The grinding wheel 12 is adjusted in the same way by turning the hand wheel 33 which operates through a mechanism exactly similar to the adjusting mechanism for the grinding wheel 13 except that the screw 32 preferably is provided with a left-hand thread in order that the direction of rotation of the hand wheels 31 and 33 may be the same for bringing the grinding wheels toward the blade strip and also the same for moving them away from the blade strip.

On the stub shafts are mounted the pulleys 34 and 35 which are driven by the belts 36 and 37

which connect the pulleys 34 and 35 with the pulleys 38 and 39. The latter pulleys are driven by any suitable source of power.

The mechanism for supporting and guiding the blade strip through the machine, keeping it in proper alignment, and for opposing the thrust of the grinding wheels is illustrated in detail in Figs. 4-9, one train of such mechanism being provided for each grinding wheel of a grinding unit. It will be assumed that the one actually described is used in conjunction with abrasive wheel 13—i. e., the first abrasive wheel in the series, although as will become apparent, that used in conjunction with abrasive wheel 12 is similar except as to certain changes that will be pointed out and except that it is reversed in position from right to left. As the blade strip M travels through the machine in the direction of the arrow (Fig. 4), any given section thereof first meets and passes under the idler roller 58 mounted in a bearing 51 and provided with a peripheral groove 52 just wide enough to accommodate the strip comfortably but without play. The strip then passes over a series of three successive rollers 53, 54, 55, all of which are alike and are illustrated in Fig. 8. Their peripheries are all in line with each other. The strip travels on the periphery of the rollers and, after leaving the roller 55, passes beneath the roller 56, which is similar to the roller 50 and, as shown in Fig. 7, is provided with a peripheral groove which acts as a guide to the strip. Each of the rollers 53, 54, and 55 is provided with a radial flange 57 and is mounted on a shaft 58 revolving in the bearing 59. The thrust block 60 in co-operation with the roller 54 takes the thrust of the grinding wheel as shown diagrammatically in Fig. 8, the strip traveling flatwise along and against it. The thrust block, as shown in Fig. 5, is adjustable toward and away from and across the plane of the flange 57, this adjustment being accomplished by the operating set screws 61 and 62 threaded in the block 63 and bearing against the thrust block itself. As these screws are turned, they either force the thrust block in the direction of the plane or allow clearance whereby it may be withdrawn by operating the screw 64. The screw 64 is always used whatever be the direction of the adjustment, to set the thrust block firmly against the screws 61 and 62. The thrust block itself shown in Fig. 9 may be provided with slots 65 to serve as water passages, and they are shaped in such a way as to direct the water stream where wanted and to reduce the liability to clogging by the lodgment of small masses of abrasive and the like. In order that these results may take place, the slots are narrower at the top as shown than they are at the bottom, and the rear wall 66 slopes toward the blade strip.

The shaft 53 on which the roller 54 is mounted is provided with a collar 67 and a set screw 68 therefor. The collar is slideable on the shaft, and therefore by utilizing the set screw the roller 54 can be set by movement axially so that it rotates in different planes. A resilient washer 69 is interposed on the shaft 53 between the roller 54 and the bearing 59, which permits the slight range of axial movement which is necessary for this adjustment. Whenever an adjustment of this character is made, the face of the thrust block is suitably shaped to accommodate the changed angle as is illustrated in Fig. 10, to be referred to.

The grinding wheel turns in the direction of the arrow (Fig. 8) and accordingly is constantly pressing the strip on the lower guide rollers, the 75

thrust being taken by the thrust block in one lateral direction, by the periphery of the roller 54 in a downward direction, and by the flange 57 in the opposite lateral direction. A stream of liquid coolant may be forced through the passage 79 at high velocity and, as it impinges the blade strip and the grinding wheel, washes loose abrasive down through the channel 71 and out through the orifices 72. Some of the stream is directed through the slots 65 as has been before mentioned.

Each grinding unit is provided with two grinding wheels, the first in order as the strip travels) grinding one facet and the second grinding the opposite facet. Fig. 7 shows the upper guide roller 56 with the strip in association therewith and showing its section after it has passed the first wheel of grinding unit A—i. e., the wheel 13. The second wheel of grinding unit A (wheel 12) and its associated mechanism is identical with the first wheel and its mechanism except that, as shown in Fig. 2 the parts are reversed in position in the unit and also with the exception that the upper guide roller corresponding to the upper guide roller 56 is provided with a peripheral groove shaped as shown in Fig. 7a; that is to say, it has convergent walls 81 between which the facets rest, the now ground edge being free from contact with the bottom of the groove. All upper guide rollers of the grinding unit A' are similar to the modification of guide roller 56—i. e., their peripheral grooves are shaped to prevent contact of the blade edge with the bottoms illustrated in Figs. 7b and 7c. The groove in guide roller 50 of grinding unit A is shaped as shown in Fig. 7.

It is contemplated that the first grinding unit shall produce a fully ground edge, the second grinding unit still further grinding this edge down. In other words, the first grinding unit brings the strip to a sharp ground edge and the second grinding unit takes still more stock from the facets, thus reducing the width of the strip. The abrasive of the second unit is a grade or more finer than that of the first grinding unit, and so, therefore, a more perfectly finished edge is produced in grinding unit A'.

In Fig. 10 is shown a thrust block modified from that of Fig. 8 by undercutting its face so that the angle of grinding is increased—that is to say, the angle subtended by the facets is greater. The pulley 54 has been adjusted so that the blade strip still travels flatwise against the face of the thrust block.

In Figs. 1, 5, and 6, there is shown a mechanism for driving the flanged rolls which support the blade so that the peripheral speed of the peripheries of the rolls is timed with the speed of the feed mechanism D. In other words, the peripheral speed of the feed rolls 80 and 81 is the same as that of the rolls 53, 54, and 55. The object is to reduce the friction on the peripheries of the guiding rolls which takes place to a considerable degree if they are merely allowed to idle. The mechanism for each guide roll comprises a spiral gear 82 fixed on the end of the shaft 58 and meshing with the spiral gear 83 fixed on the vertical shaft 84. On the lower end of the vertical shaft 84 is another spiral gear 85 meshing with a spiral gear 86 fixed on the lay shaft 87. The vertical shaft rotates in the step bearing 88 and in a bearing 89 in the bracket 90. The mechanism for each guide roller of both grinding units is identical, all being driven from a gear similar to the gear 80 on the lay shaft 87. The

lay shaft 87 is provided with a spiral gear 90 fixedly mounted on it, which meshes with a spiral gear 91 on the shaft of the feed roller 81, and the ratios of the train of gearing from the shaft 92 through to each of the guide roll shafts are properly fixed so that the peripheral speed of the feed rolls is the same as the peripheral speed of the guide rolls.

The feed rolls are geared together, the roll 81 being driven by the belt 94 through the pulley 95 on the shaft 92 and rotating therewith. On the same shaft is a spur gear 96 affixed thereto, which meshes with a spur gear 97, which rotates with the roll 80.

While I have described a certain particular construction in which my invention is incorporated, I do not desire to be limited to this particular embodiment since many changes and modifications may easily be made without departing from the spirit and scope of the invention as set forth in the following claims.

I claim:

1. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the other face of the thrust block, the peripheries of the rolls being provided with radial flanges against which the strip bears in response to pressure exerted by the grinding wheel against the margin being ground.

2. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the said face of the thrust block, the peripheries of the rolls being provided with radial flanges against which the strip bears in response to pressure exerted by the grinding wheel against the margin being ground, the rolls being adjustable axially causing the grinding angle to be changed.

3. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the other face of the thrust block, the peripheries of the rolls being provided with radial flanges against which the strip bears in response to pressure exerted by the grinding wheel against the margin being ground, the grinding wheel being mounted on a member mounted to swing transversely of the blade strip.

4. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against

one face of which the strip travels in flatwise contact therewith, the edge to be ground extending beyond the said face of the thrust block, the peripheries of the rolls being provided with radial flanges against which the strip bears in response to pressure exerted by the grinding wheel against the margin being ground, the rolls being adjustable axially causing the grinding angle to be changed, the grinding wheel being mounted on a member mounted to swing transversely of the blade strip.

5. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the other face of the thrust block, the peripheries of the rolls being provided with radial flanges against which the strip bears in response to pressure exerted by the grinding wheel against the margin being ground, the thrust block being adjustable toward and away from the path of travel of the strip.

6. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the said face of the thrust block, the peripheries of the rolls being provided with radial flanges against which the strip bears in response to pressure exerted by the grinding wheel against the margin being ground, the rolls being adjustable axially causing the grinding angle to be changed, the thrust block being adjustable toward and away from the path of travel of the strip.

7. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the other face of the thrust block, the peripheries of the rolls being provided with radial flanges against which the strip bears in response to pressure exerted by the grinding wheel against the margin being ground, the said face of the thrust block being undercut.

8. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the said face of the thrust block, the peripheries of the rolls being provided with radial flanges against which the strip bears in response to pressure exerted by the grinding wheel against the margin being ground, the rolls being adjustable axially causing the grinding angle to be

changed, the said face of the thrust block being undercut.

9. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the other face of the thrust block, the peripheries of the rolls being provided with radial flanges against which the strip bears in response to pressure exerted by the grinding wheel against the margin being ground, the grinding wheel being suspended by swinging hangers, and means for adjusting the wheel toward and away from the path of the strip.

10. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the other face of the thrust block, the peripheries of the rolls being provided with radial flanges against which the strip bears in response to pressure exerted by the grinding wheel against the margin being ground, the mechanism for propelling the strip, and mechanism adapted to rotate the rolls at a peripheral speed equal to the speed of travel of the strip.

11. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the other face of the thrust block, the peripheries of the rolls being provided with radial flanges against which the strip bears in response to pressure exerted by the grinding wheel against the margin being ground, mechanism for propelling the strip, and mechanism adapted to rotate the rolls at a peripheral speed equal to the speed of travel of the strip, said mechanism comprising a gear train operatively connecting the propelling means with the rolls.

12. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the said face of the thrust block, the peripheries of the rolls being provided with radial flanges against which the strip bears in response to pressure exerted by the grinding wheel against the margin being ground, the rolls being adjustable axially causing the grinding angle to be changed, means for propelling the blade strip, and mechanism adapted to cause the rolls to

rotate at a peripheral speed equal to the speed of travel of the blade strip.

13. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the other face of the thrust block, the peripheries of the rolls being provided with radial flanges against which the strip bears in response to pressure exerted by the grinding wheel against the margin being ground, the grinding wheel being mounted on a member mounted to swing transversely of the blade strip, feed rolls for compelling the strip, rotatable shafts on which the rolls are mounted, gears on the shafts and a gear train operatively connecting the feed rolls with the first-mentioned rolls at a peripheral speed equal to the peripheral speed of the feed rolls.

14. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the other face of the thrust block, the peripheries of the rolls being provided with radial flanges against which the strip bears in response to pressure exerted by the grinding wheel against the margin being ground, mechanism for propelling the strip, and mechanism adapted to rotate the rolls at a peripheral speed equal to the speed of travel of the strip.

15. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the said face of the thrust block, the peripheries of the rolls being provided with radial flanges against which the strip bears in response to pressure exerted by the grinding wheel against the margin being ground, the rolls being adjustable axially causing the grinding angle to be changed, the grinding wheel being mounted on a member mounted to swing transversely of the blade strip, feed rolls for compelling the strip, rotatable shafts on which the rolls are mounted, gears on the shafts and a gear train operatively connecting the feed rolls with the first-mentioned rolls at a peripheral speed equal to the peripheral speed of the feed rolls.

16. In a machine for grinding one margin of a strip of blade stock to a cutting edge, a grinding wheel, means for guiding and supporting the strip and opposing the pressure of the grinding wheel, said means comprising a series of rolls on the peripheries of which the other margin of the strip travels, a thrust block along and against one face of which the strip travels in flatwise contact therewith, the edge to be ground extending beyond the said face of the thrust block, the peripheries of the rolls being provided with radial flanges against which the strip bears in response to pressure exerted by the grinding wheel against the margin being ground, the rolls being adjustable axially causing the grinding angle to be changed, the thrust block being adjustable toward and away from the path of travel of the strip, feed rolls for compelling the strip, rotatable shafts on which the rolls are mounted, gears on the shafts and a gear train operatively connecting the feed rolls with the first-mentioned rolls at a peripheral speed equal to the peripheral speed of the feed rolls.

HERMANN HILL.
